UNITED STATES PATENT OFFICE

DOUGLAS H. KING, OF IRVINGTON, AND HAROLD T. MARTIN, OF RIDGEWOOD, NEW JERSEY, ASSIGNEES TO BELL TELEPHONE LABORATORIES, INCORPORATED, OF NEW YORK, N. Y., A CORPORATION OF NEW YORK

DESIGN FOR A WALL MOUNTING FOR A HAND TELEPHONE

Application filed June 13, 1930. Serial No. 36,045. Term of patent 14 years.

To all whom it may concern:

Be it known that we, DOUGLAS H. KING and HAROLD T. MARTIN, citizens of the United States of America, residing at Irvington, in the county of Essex and State of New Jersey, and Ridgewood, in the county of Bergen and State of New Jersey, respectively, have invented a new, original, and ornamental Design for a Wall Mounting for a Hand Telephone, of which the following is a specification, reference being had to the accompanying drawing, forming a part thereof.

The figure shown in the drawing is a per-

spective view of a wall mounting for a hand telephone showing our new design.

The body portion of the mounting is substantially elliptical in outline.

We claim:

The ornamental design for a wall mounting for a hand telephone, as shown and described.

In witness whereof, we hereunto subscribe our names this 12 day of June, 1930.

DOUGLAS H. KING.
HAROLD T. MARTIN.
